Primary Examiner — George D Kirschbaum*Assistant Examiner* — Jennifer Watkins*(74) Attorney, Agent, or Firm* — Workman Nydegger(57) **CLAIM**

The ornamental design for a shell for an orthopedic device, as shown and described.

DESCRIPTION

FIG. 1 is a perspective view of a shell for an orthopedic device, showing the design;

FIG. 2 is a left elevational view of the shell of FIG. 1;

FIG. 3 is a right elevational view of the shell of FIG. 1;

FIG. 4 is front elevational view of the shell of FIG. 1; and,

FIG. 5 is a top plan view of the shell of FIG. 1.

The broken lines are included for the purpose of illustrating environmental structure and form no part of the claimed design.
